HANDBAG

Sidney Hyman, New York, N. Y.

Application March 16, 1953, Serial No. 342,424

7 Claims. (Cl. 150—28)

1

This invention relates to new and useful improvements in handbags and handbag construction.

More particularly, the present invention proposes the construction of an improved handbag in which the bottom may be snapped into place and will be securely held in place without the necessity of gluing, stapling or sewing.

Another object of the present invention proposes forming the handbag with a perimetral shell having open upper and lower ends with a binding of flexible material over the lower end edge and an upwardly disposed edging roll spaced from the binding to provide a retainer space between the roll and the binding to hold the bottom member of the handbag in place.

Still further, the present invention proposes constructing and arranging the binding, edging roll and bottom plate of the handbag so that the bottom plate may be turned edgewise and inserted through the open lower end of the perimetral shell and then straightened into place between the roll and the binding for rapid assembly and low manufacturing costs.

As a further object, the present invention proposes arranging the edging roll so that it is held to the perimetral shell of the handbag by a cover strip which is secured at its side edge portions to the shell by the binding so that the binding and the roll may be secured in place on the shell by a single stitching or heat sealing operation.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a handbag constructed and arranged in accordance with the present invention.

Fig. 2 is a top plan view of the handbag in an opened position.

Fig. 3 is a sectional view taken on line 3—3 of Fig. 2 and with the lid partially broken away and in section.

Fig. 4 is a perspective view of the bottom member or plate of the handbag.

Fig. 5 is a perspective view of the perimetral shell of the handbag broken open with parts thereon partially broken away and with the bottom member or plate indicated in dot-dash outline.

Fig. 6 is an enlarged detail view of the edging roll and cover strip shown in Figs. 2, 3 and 5.

2

Fig. 7 is a fragmentary view similar to Fig. 5 but illustrating a modification of the present invention.

Fig. 8 is an enlarged fragmentary view of the edging roll shown in Fig. 7.

Fig. 9 is a view similar to Fig. 8 but with parts broken away to further show the construction.

The handbag, in accordance with the first form of the invention illustrated in Figs. 1 to 6, inclusive, has a perimetral shell 15, preferably of stiff material, with open upper and lower ends 16 and 17, respectively.

Shell 15, as shown, is an arcuately curved strip secured to a back member 18 of lid 19 by clasp fasteners or rivets 20 (see Fig. 5). Lid 19 is provided with a handle holding bar 21 (see Fig. 1) secured to it and a handle strap 22 is fastened to the bar 21 for carrying the handbag. A snap fastener button or post 23 (see also Fig. 2) is also secured to the lid 19 and a latching strap 24 (see Fig. 1) having one end secured as by rivets 25 to shell 15, has a coacting snap fastener socket element 26 for holding the lid in closed position.

Shell 15 may be made of cardboard, leather, thermoplastic or the like. The lid 19 and back member 18 may contain a central stiffener sheet 27 (see Fig. 3) with flexible backing sheets 28 and 29 and a tape 30 covering the edges of the sheets and stitched or otherwise secured to them. A coin holding member 31 (see Figs. 2 and 5) is secured to backing sheet 28 by rivets 32 and backing sheet 28 terminates short of the upper or outer end of the lid 19 to provide a pocket 33 on the inner side of the lid.

A stiff bottom member or plate 34 is secured in the shell 15 in the manner now to be described.

An edging roll 35 consists of a flexible cord 36, preferably a fibrous cord, covered by and secured in a strip of folded flexible material 37. The strip 37 is folded around the cord 36 with the lower edge portions 38 and 39 of strip 37 secured together by stitches 40 (see Fig. 6) beneath the cord.

A second or cover strip 41 of flexible material is folded over the edging roll 35 with the sides 42 and 43 of the strip 41 extending beyond the roll 35 and downwardly disposed adjacent the lower end edge 44 (see Figs. 3 and 5) of the shell 15 inside of the shell.

Sides 42 and 43 are secured together as by cement, glue or heat sealing beneath the edging roll 35 and sewn together by stitches 45 just under the roll 35 to hold the roll 35 firmly in place at the top of the cover strip 41.

A binding 46 on the lower end edge 44 of the shell 15 secures the cover strip 41 and the edg-

ing roll 35 to the shell. Binding 46 is a strip of flexible material folded over the lower end edge 44 of the shell and over the lower edge portions of sides 42 and 43 of the cover strip 41, the side edges 47 and 48 of binding 46 being upwardly disposed. Stitches 49, through the binding 46, cover strip 41 and shell 15 secure the cover strip 41 and edging roll 35 to the shell.

Cover strip 41 is of a width sufficient to provide a retainer space 50 (see Fig. 5) between the inner upwardly disposed side edge 47 of binding 46 and the upwardly disposed edging roll 35 to receive the peripheral edge 51 of bottom member or plate 34 of the handbag. In this manner, the flexible upwardly disposed edging roll 35 is secured to the shell 15 and spaced from the binding 46 a distance slightly greater than the thickness of the bottom plate 34.

The retainer space 50 between the binding 46 and the edging roll 35 will securely hold bottom plate 34. Moreover, the flexible binding 46 will permit the bottom plate 34 to be inserted through the open bottom end of shell 15 without separating the shell and after the shell has been fully formed. The bottom plate 34 need only to be turned and inserted edgewise into the shell and then straightened into position to seat in the retainer space 50. The binding 46 will prevent the plate 34 from going out the bottom of the shell and edging roll 35 will prevent the plate from moving upwardly in the shell.

The modification illustrated in Figs. 7, 8 and 9 is characterized by the provision of a shell 52 having an upper edge binding 53 and a lower edge binding 54 with an edging roll 55 secured to the shell 52 and spaced from the lower edge binding 54 a distance slightly greater than the thickness of the bottom member 56 of the handbag. No cover strip is used, the flexible sheet 57 of the edging roll 55 being folded around the flexible fibrous cord 58 and being sewn together and to the shell 52 at the same time by stitches 59.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a handbag, a stiff perimetral shell having open upper and lower ends, a stiff bottom plate, a flexible binding secured to the shell at its lower end, and a flexible upwardly disposed edging roll secured to the shell and spaced from the binding a distance slightly greater than the thickness of the bottom plate to hold the plate in the shell after it has been inserted through the lower end of the shell into the shell between the binding and the edging roll, said edging roll being a fibrous cord covered by and secured in a strip of folded flexible material and another strip of flexible material folded over said edging roll with edges secured together beneath the roll.

2. In a handbag, a stiff perimetral shell having open upper and lower ends, a stiff bottom plate, a flexible binding secured to the shell at its lower end, and a flexible upwardly disposed edging roll secured to the shell and spaced from the binding a distance slightly greater than the thickness of the bottom plate to hold the plate in the shell after it has been inserted through the lower end of the shell into the shell between the binding

and the edging roll, said edging roll being a fibrous cord covered by and secured in a strip of folded flexible material and another strip of flexible material folded over said edging roll with edges secured together beneath the roll, said other strip of flexible material having its secured edge portions disposed beneath the binding on the lower end of the shell.

3. In a handbag, a stiff perimetral shell having open upper and lower ends, a stiff bottom plate, a flexible binding secured to the shell at its lower end, and a flexible upwardly disposed edging roll secured to the shell and spaced from the binding a distance slightly greater than the thickness of the bottom plate to hold the plate in the shell after it has been inserted through the lower end of the shell into the shell between the binding and the edging roll, said edging roll being a fibrous cord with a strip of flexible thermoplastic sheeting folded over it and having edge portions secured together, and a second strip of flexible thermoplastic sheeting folded over the cord covering strip and secured thereto, said second strip having edge portions downwardly disposed adjacent the edge of the shell inside the shell at its lower end, said binding being a flexible strip of thermoplastic sheeting folded over the edge of the shell at its lower end and over said edge portions of said second strip and secured thereto.

30 4. In a handbag, a stiff perimetral shell having open upper and lower ends, a stiff bottom plate, a flexible binding secured to the shell at its lower end, and a flexible upwardly disposed edging roll secured to the shell and spaced from the binding
35 a distance slightly greater than the thickness of the bottom plate to hold the plate in the shell after it has been inserted through the lower end of the shell into the shell between the binding and the edging roll, said edging roll being a
40 fibrous cord with a strip of flexible sheeting folded over it and having edge portions secured together, and a second strip of flexible sheeting folded over the cord covering strip and secured thereto, said second strip having edge portions
45 downwardly disposed adjacent the edge of the shell inside the shell at its lower end, said binding being a flexible strip of sheeting folded over the edge of the shell at its lower end and over the said edge portions of said second strip and secured by stitches extending through the binding.
50

5. Closure means for the bottom end of a handbag having a perimetral shell with open upper and lower ends, comprising a stiff bottom plate, a binding folded over the lower end edge of the shell, said binding having its edges upwardly disposed, and a flexible edging roll secured to the shell and spaced from the binding a distance slightly greater than the thickness of the bottom plate to form a retainer space between the edging roll and the upwardly disposed edges of the binding to hold the bottom plate in the shell, said edging roll being a fibrous cord covered by and secured in a strip of folded flexible material, and another strip of flexible material folded over said edging roll with its edges secured together beneath the roll, said bottom plate being adapted for insertion through the lower open end of the shell into the shell for disposition of its peripheral edge between the edging roll and the binding.

70 6. Closure means for the bottom end of a hand-
bag having a perimetral shell with open upper
and lower ends, comprising a stiff bottom plate,
a binding folded over the lower end edge of the
shell, said binding having its edges upwardly dis-
75 posed, and a flexible edging roll secured to the

shell and spaced from the binding a distance slightly greater than the thickness of the bottom plate to form a retainer space between the edging roll and the upwardly disposed edges of the binding to hold the bottom plate in the shell, said edging roll being a fibrous cord covered by and secured in a strip of folded flexible material, and another strip of flexible material folded over said edging roll with its edges secured together beneath the roll, said bottom plate being adapted for insertion through the lower open end of the shell into the shell for disposition of its peripheral edge between the edging roll and the binding, the strip folded over the edging roll having a lower portion of its secured edges disposed beneath the binding on the lower end of the shell.

7. Closure means for the bottom end of a handbag having a perimetral shell with open upper and lower ends, comprising a stiff bottom plate, a binding folded over the lower end edge of the shell, said binding having its edges upwardly disposed, and a flexible edging roll secured to the shell and spaced from the binding a distance slightly greater than the thickness of the bottom

plate to form a retainer space between the edging roll and the upwardly disposed edges of the binding to hold the bottom plate in the shell, said edging roll being a fibrous cord with a strip of flexible sheeting folded over it and having edge portions secured together, and a second strip of flexible sheeting folded over the cord covering strip with edge portions extending beyond the cord, said edge portions being secured together and downwardly disposed adjacent the lower end edge of the shell inside the shell, said binding being a flexible strip of sheeting folded over the lower end edge of the shell and over a lower portion of the secured edge portions of the second strip and fastening means extending through the binding to secure the binding to the shell and to said second strip.
